GRILLE

Frederick Charles Helwig, Union, N.J., assignor to
Construction Specialties, Inc., Cranford, N.J.

Filed Feb. 16, 1971, Ser. No. 115,898

Term of patent 14 years

Int. Cl. D25—02

U.S. Cl. D54—2 B

FIG. 3

FIG. 1

FIG. 2

FIG. 1 is a top view of a representative segment of a grille embodying the design, according to the invention;
FIG. 2 is a front elevational view of the grille in FIG. 1; and

FIG. 3 is an end view of the grille in FIGS. 1 and 2.
I claim:

The ornamental design for a grille, as shown.
